(57) CLAIM

The ornamental design for package, as shown and described.

DESCRIPTION

FIG. 1 is a perspective view of a package showing a first form of my new design;

FIG. 2 is a front elevational view thereof;

FIG. 3 is a right side elevational view thereof;

FIG. 4 is a rear elevational view thereof;

FIG. 5 is a left side elevational view thereof; and,
FIG. 6 is a top plan view thereof, the bottom plan view being identical.

The package shown in the figures may preferably be used,
inter alia, for storing personal care products.
